(57) CLAIM

The ornamental design for a baby carrier, as shown and described.

DESCRIPTION

FIG. 1 is a perspective view showing our new design for a baby carrier, the portion shown in dotted lines forming no part of our design, being for illustrative purposes only.

FIG. 2 is a top view thereof;

FIG. 3 is a bottom view thereof;

FIG. 4 is a front view thereof;

FIG. 5 is a rear view thereof;

FIG. 6 is a left side view thereof; and,

FIG. 7 is a right side view thereof.

The broken lines shown on the surface of the article throughout the views are understood to represent stitching.
